APPARATUS FOR TREATMENT OF STIFF JOINTS

Henry G. White, Huntsville, Ala.

Application April 4, 1949, Serial No. 85,432

1 Claim. (Cl. 128—66)

1 This invention relates to apparatus for treatment of stiff joints.

An object of this invention is to provide apparatus for treating stiff joints whereby the treatment of the joints may be localized, the apparatus embodying means for discharging water or other liquid under pressure and at a predetermined temperature onto the joint so as to promote circulation about the joint and effect a relief of the cause which prevents free use of the limbs.

Another object of this invention is to provide apparatus of this kind which is simple in construction and is designed to be portable so that it can be attached to any water supply source.

A further object of this invention is to provide a water spray means for spraying fine streams of heated water under relatively high pressure onto a joint so as to induce circulation around the joint, the spray means including a hood or cup adapted to confine the spray to a particular area.

With the above and other objects in view, my invention consists in the arrangement, combination and details of construction disclosed in the drawing and specification and then more particularly pointed out in the appended claim.

In the drawing:

Figure 1 is a detail front elevation partly in section, of a device designed for treatment of stiff joints,

Figure 2 is a horizontal sectional view taken on the line 2—2 of Figure 1 on an enlarged scale,

Figure 3 is a vertical sectional view taken on the line 3—3 of Figure 1 on a larger scale than Figure 1, but smaller than Figure 2,

Figure 4 is a fragmentary vertical sectional view taken on the line 4—4 of Figure 1 on a scale greater than Figure 2.

Referring to the drawing, the numeral 10 designates generally a housing in the form of a closed container which is adapted to be connected by means of a pipe or tubular member 11 to a source of liquid pressure and heating supply. The housing 10 has extending therefrom an outlet pipe or hose 12, and a valve 13 is interposed in the pipe or hose 12 for regulating the flow of the liquid as will be hereinafter described.

A resilient or rubber cup 14 is connected by means of a hose 15 to the valve 13, and a normally closed or spring pressed valve 16 is interposed between the cup 14 and the outer end of the hose 15. The cup 14 has mounted therein a substantially semi-circular pipe 17 which is formed with a plurality of jet openings 18 whereby the liquid passing through the valve 16 into the pipe 17 will be discharged within the area of the cup

14 in very fine streams. The discharge pipe 17 is provided so that the needle like streams of water or other liquid will strike the area which is encompassed by the cup 14 so as to promote blood circulation around the joint.

The housing 10 has mounted thereon a liquid pressure gauge 19 for determining the liquid pressure within the housing 10 and a temperature gauge 20 is also mounted on the housing 10 for determining the temperature of the liquid passing through the housing.

In the use and operation of this invention, the pipe 11 is connected to a source of fluid pressure supply which also includes means for heating the fluid. Valve 13 regulates the amount of fluid passing through the hose 15 and when the cup 14 is engaged with a joint or other portion of a limb, the person using this device may press the spring-pressed valve 16 so that the heated liquid will be discharged in needle like streams of water onto the joint. This device has been found to be particularly useful in treatment of stiff joints caused by arthritis or the like and due to the confining area of the heated liquid a specific part of the joint or body will be subjected to the heat and liquid treatment.

I do not mean to confine myself to the exact details of construction herein disclosed, but claim all variations falling within the purview of the appended claim.

What I claim is:

Treatment apparatus for stiff joints comprising a semi-spherical cup-shaped yieldable member adapted to encompass the joint being treated, a semi-circular perforated liquid spray tube on the inside of said cup member extending across the entire inner surface thereof, and means comprising a fitting centrally positioned in said cup member connecting the center of said spray tube to a source of liquid pressure supply.
